UNITED STATES PATENT OFFICE

2,082,290

RAZORS

Edward J. Hoerres, Milwaukee, Wis.

Application September 11, 1936, Serial No. 100,362

3 Claims. (Cl. 30—44)

My invention relates to razors, and more particularly to a type known as safety razors, employing a blade fastened into an adapter.

The object of my invention is to provide a means of reciprocating the entire head of the razor in a manner to permit a shearing effect in line with the cutting edge of the blade.

Another object of my invention is to provide a device that when manually operated, will produce this reciprocating motion during the process of using the razor.

Still another object of my invention is to provide a device that is so designed as to permit the use of a standard type of blade.

A still further object is to provide a device of the character described that may be constructed economically yet affording a convenient method of assembly and permitting accessibility for the cleaning of parts and the replacement of blades.

The invention is fully disclosed in the following specification of which the accompanying drawing is a part and in which the separate parts of my improvements are designated by suitable reference characters in each of the views.

Fig. 1 is a perspective view of the assembled device.

Fig. 2 is a perspective view of the cap plate.

Fig. 3 shows a conventional type of double edge blades.

Fig. 4 is a perspective view of the blade guard.

Fig. 5 is a view of the sliding member.

Fig. 6 illustrates a wheel having serrated sides and a knurled circumferential face.

Fig. 7 is a view of the bearing screw which supports a wheel.

Fig. 8 illustrates a standard type of spring.

Fig. 9 is a perspective view of the frame and handle arrangement, and

Fig. 10 is a fragmentary cross sectional view of the entire device illustrating the operativeness of the various parts.

Similar characters of reference indicate corresponding parts throughout the several views and referring now to the same 10 shows a standard safety razor blade. It is held in position by a cap blade 11 which is provided with a projecting member 12 and two lugs 13 and 13' used for aligning the blade 10 when in position. There is a blade guide 14 provided with a center aperture 15 to receive the member 12 and two apertures 16 and 16' adapted to receive the lugs 13 and 13' on the cap blade 11. This blade guide 14 is also provided on both of its longitudinal

edges with a plurality of grooves 17 which allow the blade 10 to project outwardly thereby contacting the hair and having the grooves for protection of the skin.

A sliding member 18 engages a slot 19 in a frame and handle arrangement 20. There are tongues 21 on the member 18 which engage the grooves 22 in the slot 19 and guide its movement back and forth. A threaded aperture 23 disposed for receiving the projecting member 12 holds the blade in position. Centrally disposed in the handle arrangement is a slot 24 having apertures 25 and 25' transversely positioned. A wheel 26 provided with serrations 27 on both of its sides and a knurled circumferential face 15 is designed to fit into the slot 24 and is supported by a bearing screw 28 inserted into the apertures 25 and 25'. The sliding member 18 is also provided with a contacting pin 29 at its lower edge. This pin 29 contacts the serrations 27 on the wheel 26 by means of pressure applied by a resilient member 30.

In operation the device is assembled by placing the resilient member 30 in position in the frame 20 as shown. The sliding member 18 is then placed into the slot 19 so that the tongues 21 engage the grooves 22. Pressure is exerted on the member 18 against the resilient member 30 until the pin 29 passes the slot 24 in the handle. The wheel 26 is then placed into the slot 24 and is fastened by means of the bearing screw 28 through the wheel and the aperture 25 and 25' in the frame 20. When pressure is released the resilient member 30 will force the pin 29 on the member 18 against the serrations 27 on the sides of the wheel 26.

The blade 10 inserted between the cap blade 11 and the guard 14 is held in position and assembled with the frame and handle 20 by engaging the threaded projecting member 12 into the threaded aperture 23 and brought to a secure position so that the cutting edges of the blade 10 are in parallel relation with sliding member 18.

By using the thumb or finger to turn the wheel 26 while the razor is held in the hand the serrations 27 on the wheel 26 will actuate the contact pin 29, thus moving the entire blade assembly supported by the sliding member 18 and producing a reciprocating motion of the blade. The amount of movement is determined by the depth of the serrations and in manufacturing the device it is possible to make the serrations on one side of the wheel deeper than on the other side so as to provide more or less

reciprocating motion if the user cares to reverse the wheel. There being but one contact pin only one side of the wheel is being used and the user may elect either the deep or the shallow serrations to cause greater or less reciprocation.

While I have herein shown but a single embodiment of my invention for the purpose of clear disclosure, it is manifest that many changes may be made in the arrangement, size, and configuration of the various parts within the scope of the appended claims. What I claim and desire to secure by Letters Patent in the United States is:

- 15 1. In a safety razor a cap plate, a razor blade, a blade guard, a sliding member adapted to be fastened to said cap plate, said sliding member equipped with a contact member, a handle provided with a slot to receive said sliding member, 20 a revolving member mounted into said handle, said revolving member provided with serrations on its sides to engage the contact member on said sliding member, a resilient means mounted into the slot of said handle to provide engagement of the contact member with said revolving member causing a reciprocating motion of the blade assembly when the revolving member is brought into motion.
- 25 2. In a safety razor a cap plate provided with depending members, a razor blade provided with apertures adapted to receive the depending

members of said cap plate, a blade guard, a sliding member equipped to support said cap plate, razor blade and guard, said sliding member provided with a contact member projecting outward from same, a handle equipped with a slot to receive said sliding member, resilient means mounted into said slot for engagement with said sliding member, a revolving member supported by said handle, said revolving member supplied with a plurality of serrations on its sides to engage the contact member of said sliding member when acted upon by the said resilient member causing a reciprocating motion when said revolving member is brought into motion.

3. In a safety razor the combination with a 15 razor blade mounted between a cap plate and guard, a sliding member adapted to support said razor blade mounting, said sliding member provided with a contact member projecting outward from same, a handle equipped with a slot to 20 receive said sliding member, resilient means mounted into said slot for engagement with said sliding member, a revolving member supported by said handle, said revolving member supplied with a plurality of serrations on its sides to engage the contact member of said sliding member when acted upon by the said resilient member causing a reciprocating motion when said revolving member is brought into motion.

30

EDWARD J. HOERRES.
